UNITED STATES PATENT OFFICE.

CHARLES HAINES WILLIAMS, OF CHICAGO, ILLINOIS, ASSIGNOR TO CHICAGO RAILWAY EQUIPMENT COMPANY, OF CHICAGO, ILLINOIS, A CORPORATION.

RAIL-BRACE.

1,240,276.

Specification of Letters Patent. Patented Sept. 18, 1917.

Application filed May 28, 1917. Serial No. 171,853.

To all whom it may concern:

Be it known that I, CHARLES HAINES WILLIAMS, a citizen of the United States, and a resident of Chicago, county of Cook, and 5 State of Illinois, have invented certain new and useful Improvements in Rail-Braces, of which I do declare the following to be a full, clear, and exact description, reference being had to the accompanying drawings, 10 forming a part of this specification.

Rail braces now commonly used by railway rails, and particularly such braces as have lower portions adapted to extend beneath the bases of the rails to be braced, 15 while suitable for bracing the rails where the track is straight or of very long radius, are not well adapted for bracing the rails of short radius tracks, because the thrust receiving portions of the braces being integral with their base portions, are not adjustable with respect thereto, and if the base portions be turned or angled to bring the thrust receiving portions into proper engagement with the rails, the base portions 20 must extend diagonally with respect to the cross ties and beyond their edges.

The object of the present invention is to provide a rail brace that is adapted either for straight tracks or curved tracks of any 30 desired radius, and this object is accomplished by the novel construction hereinafter described, illustrated in the accompanying drawings, and particularly pointed out in the claims at the end of this specification.

35 Figure 1 is a plan view showing my invention applied to a short section of two rails of a track. Fig. 2 is a plan view of one form of my improved rail brace. Fig. 3 is a view in vertical section on line 3—3 40 of Fig. 2, the thrust receiving member of the brace being shown in side elevation. Fig. 4 is a plan view of the lower member of the brace. Fig. 5 is a plan view similar to Fig. 2 but showing a modified form of the invention. Fig. 6 is a view in cross section on line 6—6 of Fig. 5. Fig. 7 is a view similar to Fig. 5 but showing a modified form of the invention. Fig. 8 is a view in cross section on line 8—8 of Fig. 7. Fig. 9 is a view 45 similar to Fig. 7 but illustrating a further modification of the invention. Fig. 10 is a view in cross section on line 10—10 of Fig. 9. Fig. 11 is a plan view showing a further modification. Fig. 12 is a view in side elevation of the form shown in Fig. 11. Fig. 13

is a plan view illustrating another modification of the invention. Fig. 14 is a view in cross section on line 14—14 of Fig. 13.

Referring more particularly to Figs. 1 to 4 of the drawings, A designates the cross 60 ties whereon the rails are supported, a main rail a and a guard rail a' being illustrated.

Along the rails a and a' and at suitable distances apart my improved rail brace will be placed. Preferably, each of these braces 65 comprises a lower supporting member 20 and an upper bracing member 21. As shown, the lower member 20 is in the form of a tie plate adapted to extend beneath the rails a and a' (where two adjacent rails are used), 70 this plate being furnished with suitably disposed holes 23 to receive the spikes whereby the braces will be secured to the cross tie.

In the form of the invention illustrated in Figs. 1 to 4, the lower member 20 is offset or 75 raised as at 22 and the member 20 is formed with an elongated opening 24 to receive the upper member 21. The upper member 21, which is preferably formed as a malleable casting (having a central web and lateral 80 flanges, as shown), comprises a head portion 26 adapted to bear beneath one side of the rail, this upper member 21 having its inner wall shaped to conform to the vertical web of the rail and to the upper surface of 85 the base flange a^2 of the rail. The base of the upper member 21 is formed with a circular portion 27 corresponding approximately in diameter to the expanded portion of the elongated opening 24 (see Figs. 2 and 90 4) in the lower member 20, and beneath this circular portion 27 is formed a flange or shoulder 28 (see dotted lines Fig. 2 and full lines Fig. 3) that is of materially greater dimension than the opening 24. The flange 95 or shoulder 28 is formed with elongated slots or openings 29 (shown by dotted lines in Fig. 2) through which will pass the spikes that enter the holes 23 of the lower member and the cross tie beneath it.

100 In assembling the upper and lower members of my improved form of rail brace above described, the head portion 21 of the upper bracing member will be inserted through the opening 24 of the lower member 20 until the flange or shoulder 28 bears against the under surface of the lower member 20 and at such time the circular portion 27 of the member 21 will set within the expanded curved walls of the opening 24, as 105 110

clearly shown in Figs. 2 and 3 of the drawings. When the parts are thus assembled, the upper bracing member can be adjusted laterally with respect to the lower member 5 so as to bring the bearing surface of the upper member into proper engagement with the side of the rail and when the rail brace is spiked to the tie, the upper member of the brace will occupy such position as to most effectively resist the thrust upon the rail. By reference to Figs. 2 and 3, it will be seen that the shoulder 27^a above the circular portion 27 of the bracing member is of substantially the same width as the rear portion 24^a 10 of the opening 24 in the member 20; hence, when the upper member is adjusted laterally in either direction, the shoulder 27^a will overlap the upper surface of the plate 20, thus insuring a better interlocking of the 15 parts. Inasmuch as the upper bracing member can be adjusted laterally in either direction, it will be seen that the brace is adapted for use on either right-hand or left-hand rails and at the exact angle corresponding to 20 the rail curvature.

In the embodiment of the invention shown in Figs. 5 and 6 of the drawings, the upper bracing member 21 is adjustably connected to the lower supporting member 20 by means 30 of a pivot bolt or pintle 30 that passes through holes formed in the upper and lower members, a nut 31 serving to hold the upper member in place upon the lower member. In this form of the invention, the lower member 20 is shown as provided at one end with an upturned circular flange 32 and the base of the upper member 21 is formed with an extension 33 the end of which is upon a curve corresponding to the flange 32 against 35 which such end bears, the flange 32 being inwardly inclined to interlock with the correspondingly inclined end of the extension 33.

In the rail brace illustrated in Figs. 5 and 6, the upper member is shown as a hollow casting, formed at its base with laterally projecting flanges 35 having holes 36 therethrough to receive the spikes that enter the cross ties. The spike holes in the member 20 beneath these holes 36 will be so located as 45 to permit of the adjustment of the upper bracing member upon the lower supporting member. In the form of the invention last described, the upper bracing member being pivotally mounted upon the lower supporting member, said upper member may be turned to properly position its bearing head against the side of the rail, after which the brace will be spiked to the cross tie.

In Figs. 7 and 8, I have shown a slight 60 modification of the rail brace last described. In these figures, 20 designates the lower supporting member and 21 the upper bracing member, the head portion of which bracing member will be substantially the same as in 65 the last described form of my invention.

Instead, however, of employing a threaded bolt to unite the upper and lower members, this is accomplished by means of a rivet 30^a that passes through holes formed in the lower and upper members 20 and 21. In 70 this form of the invention, the lower member 20 is shown as provided with a curved slot 38 into which fits a downwardly projecting tongue 39 formed at the end of the base portion of the upper member 21.

In Figs. 9 and 10 of the drawings, the lower member 20 and the upper member 21 are connected by a rivet 30^a and these members are the same as in the form last described, except that the extension 33 at the base of the upper member 21 is formed with one or more teeth 40 adapted to engage with notches 41 formed in the curved raised flange 42 at the end of the lower member 20. With this form of the invention, the upper member will be adjusted at the proper angle with respect to the lower member and the engagement of the teeth 40 with the notches 41 will insure the proper retention of the parts in the adjusted position, after which the rivet 90 30^a will be headed up.

In the form of the invention illustrated in Figs. 11 and 12, the construction of the lower member 20 is the same as shown in Fig. 5 of the drawings and in this form of the invention, the upper bracing member 21 has an extension 33 that engages the upturned flange 32 of the member 20, the curved end of the extension 33 being inclined to interlock with the inclined wall of the curved flange 32, these members being connected together by a pivot bolt 30 and nut 31. In this form of the invention, however, the base of the upper member is provided with an inwardly extending floor or portion 50 to support a guard rail a' of less height than the main rail a . A filler block may be interposed between the main rail a and the guard rail a' , this block being united to the rails a and a' by through bolts. In this form of the invention, also, the upper member is shown as formed at its base with side flanges 35 having holes 36. 105 110 115

In Figs. 13 and 14 of the drawings, a further modification of the invention is shown, in which the lower member 20 is connected to the upper member 21 by forming the lower member with a circular opening having a downwardly and outwardly inclined wall adapted to receive a circular, downwardly extending boss 60 formed on the base of the upper member 21. This boss 60 has its lower portion flared outwardly as at 61 to interlock with the flared wall of the opening in the lower member 20. In this form of the invention, also, the base of the upper member is formed with a floor or extension 62 to support a guard rail a' with one of its base flanges extending over the adjacent base flange of the main rail a . The end of the 120 125 130

lower member 20 is shown as provided with a raised flange 32^a against which will bear the outer portion 21^a of the upper member 21, this outer portion 21^a of the upper member 21 being formed on a curve corresponding to that of the flange 32^a. In this form of the invention, the lower member will be provided with holes to receive spikes for attachment of the brace to the cross ties in a suitable manner. In this last described form of the invention, as in the several forms above described, the upper thrust receiving portion of the brace, being pivotally mounted upon the lower supporting member, can be adjusted to adapt it for use upon rails of any desired curvature.

What I claim as new and desire to secure by Letters Patent, is—

1. A rail brace comprising an upper bracing member having a bearing head with a flattened portion to engage the rail and a lower member adapted to be set at an acute angle to the rail, said upper bracing member being adapted to be turned to different horizontal positions with respect to said lower member.

2. A rail brace comprising an upper bracing member adapted to engage the rail and a lower member adapted to extend at an acute angle beneath the base of the rail, said upper member being mounted to turn horizontally upon said lower member.

3. A rail brace comprising an upper bracing member adapted to engage the rail and a lower member provided with an opening to admit said upper member and said upper member being provided with a part to extend through said opening and interlock with the under side of the raised end portion of the lower member at opposite sides of said opening.

4. A rail brace comprising an upper brac-

ing member adapted to engage the rail and a lower member, said lower member being provided with an opening to admit said upper member and said upper member being provided with a part to interlock with the under side of said lower member in a manner permitting the upper member to be turned to different horizontal positions with respect to the lower member.

5. A rail brace comprising an upper bracing member adapted to engage the rail and a lower member, said upper member being provided at its bottom with a circular portion passing through said lower member and with a part extending beneath said lower member to interlock therewith.

6. A rail brace comprising an upper bracing member adapted to engage the rail and a lower member formed with an elongated opening to receive said upper member, said opening having curved, expanded walls and said upper member being formed at its bottom with a circular portion extending through said curved walls of the lower member and with a flange or offset to engage the under side of said lower member.

7. A rail brace comprising an upper bracing member adapted to engage the rail and a lower member provided with an opening wherein said upper member is pivotally held, said upper member being provided at its bottom with a flange having cutaway portions for the passage of spikes.

8. A rail brace comprising an upper bracing member adapted to engage the rail and a lower member adapted to extend beneath the base of the rail, said lower member being provided with an offset portion having an opening to receive the upper member and said upper member being provided with a flange to interlock with said lower members.

CHARLES HAINES WILLIAMS.
